TOY RING LAUNCHING DEVICE

Clarence F. Hartman, Silverton, Ohio

Application October 28, 1949, Serial No. 124,139

4 Claims. (Cl. 124—17)

1

This invention relates to a toy ring-launching device.

An object of the invention is to provide a toy which may simulate a firearm and which will forcibly propel, launch or eject a ring-like projectile which is given a reverse spin incident to being expelled from the device.

In those instances wherein the projectile is launched in a vertical plane upon a supporting surface, such as a floor, it will travel away from the operator until its forward motion is overcome by the reverse spin of the ring, whereupon it will automatically return to the operator, thereby providing a boomerang effect.

In those instances wherein the projectile is launched in a horizontal plane, the reverse spin will impart a gyroscopic effect which will maintain the projectile in a horizontal plane throughout its flight, thereby adapting it for use with various ring-toss games.

Another object of the invention is to provide a toy ring-launching device wherein an elastic band is utilized as the ring-launching and spinning media.

A further object of the invention is to provide a toy ring-launching device which is sturdily constructed in such a manner as to provide an inexpensive quality toy item which may be manufactured using modern mass-production techniques.

Still a further object of the invention is to provide a device having the hereinabove described characteristics and which will positively retain a ring-like projectile against accidental or unintentional ejection until launched by a positive act on the part of an operator.

These and other objects are attained by the means described herein and as disclosed in the accompanying drawings, in which:

Fig. 1 is a side elevation of a device embodying the teachings of the present invention.

Fig. 2 is a longitudinal section view of the device of Fig. 1 with the operating parts shifted to a ring-launching position.

Fig. 3 is a fragmentary section taken on line 3—3 of Fig. 1.

With reference now to Figs. 1 and 2, it will be noted that the device may simulate a firearm, including a hand grip portion 19 terminating in a forwardly and downwardly projecting substantially quadrantal arc-shaped housing 12 which may be considered as including bottom walls 14 and 16 and a pair of laterally spaced side walls 18 which collectively define a substantially U-shaped base or track member dimensioned to receive a portion of rim 19 of a ring-like projectile denoted generally by the numeral 20.

It will be observed that bottom wall 14 is substantially horizontal, whereas wall 16 is arcuate,

2

approximating the contour of housing edge 22, from which it is laterally spaced, see Fig. 2. Walls 14 and 16 are not continuous, being spaced as at 24.

An actuator element denoted generally by the numeral 30 is provided in slidably, overlapping relationship with bottom wall 14. Element 30 may be fabricated from a length of flat resilient spring stock, one end of which may be pivotally secured as at 32 to a trigger member denoted generally by the numeral 34.

In the preferred embodiment of the invention the inner end of the actuator element may be provided with a looped portion 36 dimensioned to be loosely received within a complementary circular notch portion 38 of the trigger. The trigger member may be pivotally secured as at 40 to hand grip portion 18.

A spring 42, one end of which may be affixed to trigger 34 as at 44 and the other end fixed relative to housing 10 as at 46 may be provided for normally and yieldably urging the trigger to the fully retracted position illustrated in Fig. 1. A stop element 48 may be provided for limiting the rearward travel of the trigger.

As best disclosed in Fig. 2, the forward portion of actuator element 30 passes under and is deflected downwardly by the free lower end 50 of wall 16, thence onto and across bottom wall 14.

The upper end of the housing is provided with an abutment 52, which preferably extends forwardly from the upper portion of wall 16, as illustrated.

With reference now to Fig. 1, it will be noted that when the ring-like projectile 20 is received within the U-shaped base or track member, it will rest upon actuator element 30, engage abutment 52 and be maintained in the plane of side walls 18.

The projectile may be yieldably retained in this position by means of an elastic band 60 which may be secured to and carried by the outer or forward end of housing 12. For convenience of assembly and ease of replacement of the band, a band receptive T-slot 62 may be provided as best illustrated in Fig. 1.

The physical characteristics of band 60 are such as to enable it to be stretched over ring 20. When the band is located in the diametric relationship with the ring, as illustrated in Fig. 1, it will yieldably position the ring in a condition of equilibrium with respect to the base or track member, that is, the ring will have a tendency to remain in a condition of status quo in a plane in parallelism with side walls 18.

When it is desired to launch ring 20, trigger 34 is pulled for moving actuator element 30 forwardly over bottom wall 14 for imparting a turning force to the ring which will shift the upper end of the band toward the hand grip portion

and out of its diametric relationship with the ring. As the band is thus shifted toward the hand grip portion, its potential energy will be transferred to kinetic energy as the band suddenly snaps downwardly for imparting a combined spinning and ejecting force to the ring sufficient to propel it forwardly from the housing.

The ring, if launched in a vertical plane, will move outwardly on a floor or other supporting surface until its forward motion has been overcome by the reverse spin of the ring, whereupon it will automatically roll back along its initial path toward the operator.

When the ring has been launched in a horizontal position, the back spin imparted thereto, incident to its launching operation, will impart a gyroscopic effect to the ring which will maintain it in a horizontal plane throughout its flight, thereby enabling the ring to be successfully used in various ring-toss games such as, by way of example, quoits, ring-the-clown's-nose, and the like.

I have observed that best results are obtained when the ring projectile is supported in two places located approximately 90 degrees apart, such as at abutment 52 and actuator element 30 which overlies bottom wall 14, however, I do not wish to be limited to such relationship, it being understood that abutment 52 could, if desired, be omitted, whereupon a substantial portion of the outer periphery of rim 19 would be engaged by the launching device. Wall 16 and wall 70, as illustrated in Fig. 2, serve to effectively close off the interior of the housing against the insertion of foreign objects which might impair the operating characteristics of the device. In this connection it should be understood that wall 16 could be omitted and a laterally projecting abutment element provided in lieu of lower end 50 of wall 16.

What is claimed is:

1. A ring projectile launching device comprising a hand grip portion including a forwardly and downwardly projecting housing defined by a bottom wall and a pair of laterally spaced side walls dimensioned to receive a portion of the rim of a ring projectile, an actuator element located in said housing between the side walls and slidably engaging the bottom wall thereof, an elastic band secured to and carried by the forward end of said housing, said band stretchable over and in diametric relationship with a ring seated in said housing for yieldably urging it against said actuator element and for disposing it in a plane in parallelism with the side walls of said housing, and means operable from the hand grip portion for shifting said element axially of said ring housing for rotating said ring within and relative to said housing for shifting said band from its diametric relationship with the ring toward said hand grip portion for simultaneously applying a spinning and propelling force to the ring sufficient to eject it from the housing.

2. A ring projectile launching device comprising a hand grip portion including a forwardly and downwardly projecting housing defined by a bottom wall and a pair of laterally spaced side walls dimensioned to receive a portion of the rim of a ring projectile, an abutment spanning said side walls remote from said bottom wall, an actuator element located in said housing between the side walls and slidably engaging the bottom wall thereof, an elastic band secured to and carried by the forward end of said housing, said

band stretchable over and in diametric relationship with a ring seated in said housing for yieldably urging it against said actuator element and abutment for disposing it in a plane in parallelism with the side walls of said housing, and means operable from the hand grip portion for shifting said element axially of said ring housing for rotating said ring within and relative to said housing for shifting said band from its diametric relationship with the ring toward said hand grip portion for simultaneously applying a spinning and propelling force to the ring sufficient to eject it from the housing.

3. A ring projectile launching device comprising a hand grip portion including a forwardly and downwardly projecting housing defined by a bottom wall and a pair of laterally spaced side walls dimensioned to receive a portion of the rim of a ring projectile, an actuator element located in said housing between the side walls and slidably engaging the bottom wall thereof, means operable for maintaining said element in contacting relationship with said bottom wall, an elastic band secured to and carried by the forward end of said housing, said band stretchable over and in diametric relationship with a ring seated in said housing for yieldably urging it against said actuator element and for disposing it in a plane in parallelism with the side walls of said housing, and means operable from the hand grip portion for shifting said element axially of said ring housing for rotating said ring within and relative to said housing for shifting said band from its diametric relationship with the ring toward said hand grip portion for simultaneously applying a spinning and propelling force to the ring sufficient to eject it from the housing.

4. A ring projectile launching device comprising a hand grip portion including a forwardly projecting, channeled, substantially quadrantial arc shaped member dimensioned to receive the peripheral portion approximating one quadrant of the rim of a ring projectile, a continuous one piece elastic band secured to and carried by that end of the member remote from the hand grip portion, said band stretchable over and in diametric relationship with said ring for positioning it in endwise upstanding relationship on said member and in a condition of equilibrium with respect thereto, reciprocable means disposed in said channel engageable by the ring received in said member, and means for imparting linear movement to said reciprocable means for rotating said ring relative to said member for shifting said band rearwardly toward the hand grip portion out of its diametric relationship with said ring for applying a combined rotating and compelling force to the ring to bodily eject it from said device.
